United States Patent

Des. 240,618
Patented July 20, 1976

240,618

CONDUCTOR EDUCATIONAL BOARD

Douglas C. Covert, Royal Oak, Mich., assignor to
Xerox Corporation, Stamford, Conn.

Filed Dec. 27, 1973, Ser. No. 428,646

Term of patent 14 years

Int. Cl. D19—07

U.S. Cl. D19—62

FIG. 1

FIG. 2

FIG. 1 is a right side perspective view of a conductor educational board showing my new design; and

FIG. 2 is a left side perspective view thereof.

The rear of the educational board not shown is plain and unornamented.

I claim:

The ornamental design for a conductor educational board, substantially as shown and described.
